UNITED STATES PATENT OFFICE.

JOSEPH A. GROEBLI, OF NEW YORK, N. Y., ASSIGNOR TO KURSHEEDT MANUFACTURING COMPANY, OF NEW YORK, N. Y., A CORPORATION OF NEW YORK.

TENSION MECHANISM.

No. 926,250.

Specification of Letters Patent. Patented June 29, 1909.

Application filed January 28, 1907. Serial No. 384,357.

To all whom it may concern:

Be it known that I, JOSEPH A. GROEBLI, a citizen of the United States, residing in the city, county, and State of New York, have 5 invented new and useful Improvements in Tension Mechanism, of which the following is a specification.

My invention relates to tension mechanism especially applicable to embroidering 10 machines, although it may be used in connection with other characters of machines.

My invention in the form shown by way of illustration in the drawing consists in mechanism suitably operated and exerting a 15 variable tension upon the threads.

The mechanism may be variously operated either by hand as shown, or automatically by pattern or jacquard mechanism. A 20 type of mechanism suitable for the purpose is shown in Patent No. 593,207, for embroidering machine, dated November 9, 1897, granted to the Kursheedt Manufacturing Company as my assignee.

It will be understood that the mechanism 25 shown is but one form of my invention and will be specifically described without limiting myself thereto.

In the drawing:—Figure 1 is a broken away plan view of a needle rail carriage of 30 an embroidering machine with take up and tension mechanism forming part of this invention: Fig. 2 is a side elevation of the mechanism shown in Fig. 1: Fig. 3 is a detail view of part of the tension mechanism 35 showing the variable tension device with which the threads coöperate in a position different from that shown in Figs. 1 and 2:—and, Fig. 4 is a side elevation of a different form of needle and take up mechanism in combination with the variable tension.

In Figs. 1 and 2, A indicates the movable carriage which carries the needle, take up and tension devices.

The needle rail *a* carries the needles *b*. 45 Carried also by the carriage A is a spool rest *c* supporting rotary spools *d*. A take-up bar or wire *e* is carried on arms *f* on the rock shaft *g*, which rock shaft is operated in any suitable or ordinary manner. Located pref- 50 erably between the spool and the take up is a variable tension device indicated generally by the letter *h*. This tension device may assume a multitude of forms, not herein illus- trated. In the present instance the variable 55 tension is shown as consisting of a plurality

of wires, bars, rods or tubes *i* *j* or their equivalents capable by movement to increase or decrease the extent of contact of the threads circumferentially or peripherally with the said bars. The rods are also shown by way 60 of example as round and having their axes in fixed relation to each other during all the movements of the variable tension.

The bar *j* is in the present instance a rotatable shaft carried in bearings *l* (only one of 65 which is shown) and carries disks or arms *m* at intervals thereon, which disks or arms carry the bar *i* whose axis is at a fixed distance from the axis of bar *j*. In Figs. 1 and 2 the bars are shown in one position and 70 in Fig. 3 they are shown as swung into another position where a greater length of thread *r* presses against the peripheral surfaces of the bars. This will increase the tension on the threads. The bar *j* thus rotates 75 on its axis and the bar *i* revolves about the axis of the bar *j*. As the bar *i* is in this instance shown maintained in a fixed position with respect to the bar *j* it does not revolve about the bar *j* but only about the axis of 80 the said bar *j*.

Rotary movement is imparted to the bar *j* in any suitable manner as by means of a pinion *n* and a worm *o*. The worm *o* is carried on an upright shaft *p* having an adjusting arm *q* which may be operated by hand or otherwise. Or the shaft or bar *j* may be extended as shown in dotted lines in Fig. 1 or otherwise arranged or connected to readily 85 accommodate it for connection with the jacquard adjusting mechanism. Means for braking the spools in their rotation are provided, shown in the present instance, as a rock shaft *s*, suitably located with respect to the spools and carrying a series of blades *t* 90 adapted to be brought against the respective spools in any ordinary or usual manner.

In Fig. 4 I have shown another construction wherein the needle rails *a* are carried by reciprocating slides *u* carried in bearings *V*, and coöperating with a plurality of take up bars or wires *e* *e* which are suitably operated in any of the well known ways.

The variable tension *h* is, as before, combined with the take up motion and is in advance thereof and between the same and the spool *d*. The mode of operation of the mechanisms described and illustrated will be obvious from the said description and illustration.

Having described my invention what I claim and desire to secure by Letters Patent is: -

An embroidering machine embodying a needle mechanism, a tension device, comprising a plurality of friction bars with the peripheries of which the threads contact, one of which bars is located in a fixed position with relation to the path of the thread from the supply and means for moving the other of said bars about the axis of the first bar to change the extent of peripheral contact of

the thread with said bars and take up mechanism for said thread interposed so as to act upon the thread between the needle mechanism and said stationary tension bar. 15

Signed at New York, in the county and State of New York, this 26th day of January, 1907.

JOSEPH A. GROEBLI.
